(57) **CLAIM**

The ornamental design for an electronic meter with graphical user interface, as shown and described.

DESCRIPTION

1.0-2.0 Electronic meter with graphical user interface
FIG. 1.0 is a front view of a first embodiment of an electronic meter with graphical user interface; and
FIG. 2.0 is a front view of a second embodiment thereof. The claimed design relates to a display interface of a temperature and humidity monitoring electronic meter. The broken lines are included for the purpose of illustrating portions of the electronic meter with graphical user interface that form no part of the claimed design.
